PANEL FOR PREFABRICATED HOUSES

Alan D. Roush, Dayton, Owen M. Stoltz, near Dayton, and John D. Yeck, Dayton, Ohio, assignors to General Building Units, Inc., Dayton, Ohio, a corporation of Ohio

Application May 6, 1947, Serial No. 746,342

3 Claims. (Cl. 189—86)

1

This invention relates to building construction and more particularly to panel members and the supporting structure therefor.

An object of this invention is to provide panel members for building units, such that the panel members may be used to simulate the appearance of lap siding or they may be used to simulate sheeting or other wall structure wherein the panels have the appearance of uniform thickness throughout.

Another object of this invention is to provide panel members having joints so arranged as to deter the ill effects of capillary attraction.

Another object of this invention is to provide a structure such that the panels may be snapped into permanent position on suitable retainers forming a part of the supporting structure in such a manner that after the panels have been snapped into position, they are locked in position to prevent removal thereof without mutilation of one or more of the parts associated therewith.

Other objects and advantages reside in the construction of parts, the combination thereof and the mode of operation, as will become more apparent from the following description.

Referring to the drawings,

Figure 1 is a fragmentary, perspective view of the panels and a supporting studding.

Figure 2 is another fragmentary, perspective view similar to Figure 1, wherein the panels have been mounted to simulate lap siding.

Figure 3 is a fragmentary view of interlocking panels adapted to deter capillary attraction, showing parts in section.

Figure 4 is a view similar to that shown in Figure 3, having the panels mounted in offset relation so as to simulate lap siding.

Figure 5 is another modification showing panels simulating lap siding arranged to deter capillary attraction.

In the drawings, the reference character 10 is used to indicate a channel-shaped studding having the side 12 forming the bottom of the channel, the side walls 14 and 16 and the reentrant flanges 18, leaving a longitudinal slot 20. The side 12 of the studding 10 has struck out therefrom panel-supporting hooks 22, the main bodies of which are substantially triangular shaped, joined at the bottom to the studding by a leg portion 24. An opening 26 is formed in the side 12 when the supporting hook 22 has been projected outwardly. The panel-supporting hooks 22 extend outwardly in a direction normal to the side 12, so as to provide rigid supports for the panels. Retaining members or tongues 30 are

also struck out from the side of the studding 10; but instead of being directed outwardly in a direction normal to the side 12, the tongues 30 are angularly disposed, so as to yield in response to a pressure directed normal to the side 12.

Panel members 40, as shown in Figure 1 and 2, have been provided with saw tooth-like flange portions 42 extending along the bottom thereof and saw tooth-like flange portions 44 extending along the top of each panel. The saw tooth-like flange portions 42 may consist of two or more upwardly directed ribs 46, leaving a pair of grooves 48 on the underside.

As may best be seen in Figure 1, the panels have been positioned so as to present a substantially flush surface forming a wall. This has been accomplished by nestling the ribs 46 of the upper flange 44 of the lower panel into the grooves 48 of the inwardly directed flange 42 along the bottom of the upper panel. By this arrangement, the hook 22 underlies one of the grooves 48 of the upper and lower flanges. After the panels have been mounted in position, the tongues 30 spring over the innermost ribs 46, so as to lock the panels in position.

As may be best seen by referring to Figure 2, the panels may be mounted so as to simulate lap siding by utilizing only one groove of the lower flange of an upper panel. By this arrangement, the tongues 30 lock only the upper flange of each panel on its hook.

This arrangement permits the use of identical flanges for both the exterior and the interior of a building. By arranging the panels as disclosed in Figure 1, these panels may be used either on the exterior or the interior. By arranging the panels as shown in Figure 2, the panels may then be used on the exterior to simulate lap siding.

In the modification disclosed in Figures 3 and 4, the panel member 60 has been provided with a corrugated, flange-like portion 62 extending along the bottom. The corrugation forms an inverted valley-like portion extending along the bottom of the panel. The upper portion of each panel is provided with an inwardly directed flange portion 64 joined to an inverted channel portion 66, terminating in an L-shaped portion 68. The studding is provided with a tongue-like portion 70 provided with a tooth 72 projecting into the inverted channel portion 66. By this arrangement, line contacts are made along the lines 80, 82 and 84, as best seen in Figure 3, between the upper portion of one panel and the lower portion of the panel directly above. This line contact practically eliminates capillary attraction, thereby pre-

venting moisture from being drawn between contacting portions of adjoining panels. By positioning the panels as shown in Figure 3, the panels may be made to simulate boards. By positioning the panels as shown in Figure 4, the panels simulate lap siding.

In Figure 5 another modification has been shown. This modification may be used with studdings 10, substantially identical to those disclosed in the preferred embodiment. The upper margin 10 of the panel 90 is provided with an inwardly directed flange portion 92 and a reentrant flange portion 94 hooked upon the tongue 96. In order to obtain a line contact and at the same time have the panels 90 simulate lap siding, the lower margin 15 of the panel 90 is provided with a curved flange 98 simulating an inverted valley-like portion, making line contacts along the lines 100 and 102 of the adjacent panels. Thus, it can be seen that by utilizing a marginal flange consisting of 20 several portions forming sharp corners and a second marginal flange where the portions are curved, a line to line contact may be made between the adjacent panels, thereby eliminating the deleterious effects caused by capillary attraction.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described our invention, we claim:

1. In a wall structure, the combination including vertically disposed supports, a plurality of panel members simulating the appearance of lap siding, each of said panel members including inwardly directed portions on two opposite sides thereof, one of said portions being undulated so as to be nested with an inwardly directed portion of an adjacent panel member, the other of said portions forming substantially right angle corners, the distance between corners being less than twice the radius of curvature of the undulating portions, the panel members being horizontally disposed one above the other with the undulating portion extending along the lower edge of the 45 panel members, the corners being located along

the top of each panel member, the corners of each succeeding lower panel member being seated in a concave portion of one of the undulations of the panel member immediately above so that the panel members simulate the appearance of lap siding, and means for fixedly securing the panel members to the vertically disposed supports.

2. In a wall structure, the combination including a plurality of panel members simulating the appearance of lap siding, each of said panel members including inwardly directed portions along the top and the bottom thereof, the portion along the bottom forming a concave inverted valley-like portion extending along the bottom of the panel member, the upper portion being angularly disposed forming a channel portion provided with corners, the corners of each of the underlying panel members projecting into the inverted valley-like portion of the panel member directly above, the corners of the inverted valley-like curved portion forming two line contacts.

3. A wall assembly including a studding of sheet metal having outwardly directed supporting hooks struck out of the wall of the studding, a plurality of horizontally disposed panel members simulating lap siding, each of said panel members including an inwardly directed portion along the bottom thereof, which inwardly directed portion forms a concave curve resulting in an inverted valley-like portion, the upper portion of each panel member being angularly disposed forming a channel portion provided with corners, the corners of each of the lower panel members projecting into the inverted valley-like portion of the panel member directly above, the channel portion resting upon the supporting hooks projecting upwardly from the wall for supporting the panel members upon the studding.
